Primary Examiner — Terry A Wallace

(74) *Attorney, Agent, or Firm* — Middleton Reutlinger

(57) **CLAIM**

The ornamental design for a cooler, as shown and described.

DESCRIPTION

FIG. 1 is a front perspective view of a cooler design; FIG. 2 is a rear perspective view of the cooler design of FIG. 1;

FIG. 3 is a front view of the cooler design of FIG. 1; FIG. 4 is a rear view of the cooler design of FIG. 1; FIG. 5 is a first side view of the cooler design of FIG. 1; FIG. 6 is a second side view of the cooler design of FIG. 1; FIG. 7 is a top view of the cooler design of FIG. 1; FIG. 8 is a front perspective view of the cooler design with the lid in an open position; FIG. 9 is a rear perspective view of the cooler design of FIG. 8; FIG. 10 is a front view of the cooler design of FIG. 8; FIG. 11 is a rear view of the cooler design of FIG. 8; FIG. 12 is a first side view of the cooler design of FIG. 8; FIG. 13 is a second side view of the cooler design of FIG. 8; and,

FIG. 14 is a top view of the cooler design of FIG. 8. The broken line disclosure represents unclaimed boundary and/or portions of the cooler in which the design is embodied.

1 Claim, 14 Drawing Sheets
